UNITED STATES PATENT OFFICE.

WILLIAM EARNEST, OF GARYVILLE, LOUISIANA.

LOGGING APPARATUS.

No. 806,246.

Specification of Letters Patent.

Patented Dec. 5, 1905.

Application filed September 7, 1905. Serial No. 277,436.

To all whom it may concern:

Be it known that I, WILLIAM EARNEST, a citizen of the United States, residing at Garyville, in the parish of St. John the Baptist and 5 State of Louisiana, have invented new and useful Improvements in Logging Apparatus, of which the following is a specification.

My invention has reference to logging apparatus; and it has for one of its objects to 10 provide a simple and inexpensive apparatus through the medium of which logs may be expeditiously gathered.

Another object of the invention is the provision of a chain-holder or device for connecting a log to the gathering-cable at an intermediate point in the length of the latter, and this without subjecting the said cable to frictional wear.

With the foregoing in mind the invention 20 will be fully understood from the following description and claims, when taken in connection with the accompanying drawings, forming part of this specification, in which—

Figure 1 is a perspective view illustrating 25 my novel apparatus and the mode of using the same in moving two logs. Fig. 2 is an enlarged side elevation of the novel chain-holder. Fig. 3 is a transverse section taken through the chain-holder in the plane indicated by the line 3 3 of Fig. 2.

Similar letters designate corresponding parts in all of the views of the drawings, referring to which—

A A are elevated cables stretched between 35 trees or other supports. B is a block suitably arranged and movable on the said cables and carrying a sheave or pulley C. D is a cable passed over the said sheave or pulley C and provided at one end with tongs E for taking hold of a log, as shown, and designed to 40 be connected to any suitable means for moving the log. F is a chain fastened about a second log, and M is the chain-holder or device for effecting connection between the 45 chain F and the cable D at an intermediate point in the length of the latter.

As best shown in Figs. 2 and 3, the chain-holder or connecting device M comprises a body *a* and a circumferentially-grooved anti-friction-roller *b*. The body *a* is preferably formed of a bar of iron or other suitable material bent into loop form and has a lower contracted bight portion *c* and an upper comparatively wide or open portion *d*. Between 50 the ends of the legs of the body-loop the anti-

friction-roller *b* is mounted, as shown, the said roller being preferably arranged on a bolt *e*, extending through the said ends of the loop-legs.

The cable D is passed through the body of 60 the chain-holder or connecting device M, and when it is desired to connect a log to the said cable at an intermediate point in the length thereof the chain F is passed through the upper comparatively wide or open portion of 65 the body *a*, and one of the links of the chain is drawn down into the contracted bight portion of the said body *a*. With this done it will be observed that there is no liability of the said chain F being casually released from the 70 holder M, and it will also be observed that as the cable D is drawn through the holder or connecting device M the said cable will bear against the roller *b*, and hence will not be subjected to frictional wear. The cable D is 75 drawn through the chain-holder or connecting device M until the tongs E bring up against the said holder or connecting device, after which the two logs will be moved together on the elevated cables and through the medium of 80 the cable D.

It will be apparent from the foregoing that when my novel apparatus is used as described logs may be expeditiously gathered with but little effort on the part of the attendants, and 85 it will also be apparent that when the logs reach the point desired the tongs E may be quickly and easily disengaged from one log, and the chain F may then be readily taken out of the holder or connecting device M and removed from the other log.

Having described my invention, what I claim, and desire to secure by Letters Patent, is—

1. In a logging apparatus, the combination 95 of an elevated support, a block movable on said support and carrying a sheave, a cable passed over the said sheave and provided at one end with means for fastening it to a log and adapted to be connected to suitable log-hauling means, and a chain-holder or connecting device comprising a loop-shaped body having a lower contracted bight portion and an upper comparatively wide or open portion; receiving the before-mentioned cable, and an 100 anti-friction-roller mounted in the body at the upper end of the comparatively wide or open portion thereof and arranged to bear on the said cable.

2. As an article of manufacture, a chain- 110

- holder or connecting device for use in logging apparatus; the same comprising a loop-shaped body having a lower contracted bight portion and an upper comparatively wide or open portion, and an antifriction-roller mounted in the body at the upper end of the comparatively wide or open portion thereof and arranged to bear on a cable extending through the said portion.
- 10 3. As an article of manufacture, a chain-holder or connecting device for use in logging apparatus; the same comprising a body formed of a metallic bar bent into loop form, and having a lower contracted bight portion and a 15 comparatively wide or open portion, and an

antifriction-roller mounted between the ends of the said bar.

4. In a logging apparatus, the combination of an elevated support, a block movable on said support and carrying a sheave, a cable passed over the said sheave, and a chain-holder or connecting device loosely receiving the said cable.

In testimony whereof I have hereunto set my hand in presence of two subscribing witnesses.

WILLIAM EARNEST.
